(57) **CLAIM**

The ornamental design for a folding tree mounted portable hoist, as shown and described.

DESCRIPTION

FIG. 1 is a left, front and top perspective view of the folding tree mounted portable hoist;

FIG. 2 is a left, rear and top perspective view thereof;

FIG. 3 is a front elevation view thereof;

FIG. 4 is a left elevation view thereof;

FIG. 5 is a right elevation view thereof;

FIG. 6 is a top plan view thereof; and,

FIG. 7 is a bottom plan view thereof.

A folding tree mounted portable hoist for lifting heavy objects in the field, including a chain for connection to a tree. The broken lines depict environment and are included for illustrative purposes only and form no part of the claimed design.
